UNITED STATES PATENT OFFICE.

NORMAN HOWARD CAUFIELD, OF VICTORIA, BRITISH COLUMBIA, CANADA.

STOOKER.

Application filed June 2, 1922. Serial No. 565,347.

To all whom it may concern:

Be it known that I, NORMAN HOWARD CAUFIELD, a subject of the King of Great Britain, residing at the city of Victoria, 5 in the Province of British Columbia, Canada, have invented certain new and useful Improvements in Stookers, of which the following is a specification.

My invention relates to improvements 10 in stookers, and the object of my invention is to devise a stooker adapted to form the sheaves delivered to it from the binder in a quick and practical manner and to then dump the stooks in a vertical position with 15 the maximum of efficiency, which is automatic in operation, simple in construction and free from complexity, and in which the number of parts is reduced to a minimum, thereby enabling it to be manufactured and 20 sold at a comparatively low cost and to be maintained with the minimum of expense.

I attain this object by the construction illustrated in the accompanying drawings in which—

25 Fig. 1 is a side elevation of the stooker, in the sheaf-receiving position.

Fig. 2 is a plan view.

Fig. 3 is an end view.

30 Fig. 4 is a side elevation of the basket just before dumping.

Fig. 5 is a side elevation of the basket after dumping and just before returning to the normal position.

35 Figs. 6 and 7 are views illustrating the supporting of the fork plate during return of the basket to normal position.

Fig. 8 is a side view looking on the inner side of the sprocket driving gear.

40 Fig. 9 is an edge view of Fig. 8.

Fig. 10 is an end view of the fork plate and levers, the frame being in section.

Fig. 11 is an enlarged detail view of a cam, in elevation.

45 Similar numerals of reference indicate similar parts throughout the several views.

1 indicates a horizontal frame, substantially U-shaped, on which the machine structure, now to be described, is mounted, which frame is provided on the side remote from 50 the binder with a main traction wheel 2, the opposite side of the frame being connected to the binder by any suitable means so that it travels along with the binder when the same is in operation, as will be well understood. Secured to the traction wheel 2 and rotatable therewith is a sprocket wheel

3 chain-connected to a sprocket 4 rotatably mounted on a shaft 5 rotatably mounted on the traction wheel side of the frame 1 in a bearing 6 secured to the frame. The 60 sprocket 4 has fastened to it on its inner face a clutch 7 formed out of a disc arranged concentrically on the sprocket and dished on its inner face to form an inwardly extending rim 8, in which rim is cut a number of spaced notches 9, there being preferably twelve such notches, forming clutch teeth with any of which a spring-pressed pawl 10 pivotally connected to an arm 11 secured to the shaft 5 may be engaged when 70 required, as more fully described later, the opposite end of which pawl is extended at right angles, as at 12, and this extended end 12 is normally engaged by the end of a lever 13 fulcrumed on an arm 14 extending 75 substantially at right angles to the arm 11 and integrally connected to it, the opposite end of the lever 13 normally resting on a laterally movable spring-pressed rod 15 mounted on the front end of the frame, and 80 when the lever 13 is thus engaging the rod 15 the pawl 10 is held out of engagement with the clutch disc 7, the shaft 5 being then stationary. The rod 15 may be with drawn laterally by any suitable means, such 85 as a bell crank 16 connected to the rod and suitably supported on the frame, the bell crank being operated by means of a rod 17 led to within easy reach of the operator on the binder.

18 and 19 indicate stud shafts secured in brackets 20 and 21 secured respectively on opposite sides of the frame, which shafts extend inwardly and on which are rotatably mounted respectively sleeves 22 and 23 each 95 of which sleeves is provided at its inner end with a plate bar, 24 and 25, which bars lie normally vertical when the machine is in the normal or sheaf-receiving position, as shown in Fig. 1; and to the upper and 100 lower ends of these bars upper and lower side bars 26—27 and 28—29 are secured. The upper bars 26 and 28 are substantially horizontal while the lower bars 27 and 29 are inclined upwardly towards the rear, that is, when the machine is in the normal 105 position, and the rear ends of these bars are bent inwardly so that the bars are closer together at their rear ends than at their front ends and thus the sides of the basket taper inwardly towards the rear, the sides being formed by the side plates 30 and 31.

connected directly at their rear ends to the rear ends of the bars 26-27 and 28-29 while their front ends are connected to vertical bars 32 and 33 connecting the front ends of the bars 26-27 and 28-29. The upper edges of the side plates 30 and 31 are turned over at right angles to form outwardly extending flanges or lips 34 and 35, as shown in Fig. 2, and secured to the side plates adjacent their rear ends on the inside are plate springs 36 and 37 curving inwardly into the interior of the basket, which springs act to exert a slight side pressure on the stool, as will be referred to later.

To the bars 32 and 33 are secured vertically arranged L-shaped brackets 38 and 39 the upper ends of the vertical portions of which lie substantially in the same plane as the lips 34 and 35 of the side plates and to these vertical portions 40 and 41 are pivoted the lower ends of normally vertical bars 42 and 43 between which is secured a concavo-convex plate 43^a which forms the front closure plate of the basket, that is, the front when dumping, and these bars are automatically swung about their pivoted lower ends to carry the front plate to open or close the basket by means of bars, indicated generally by the numerals 44 and 45, the upper ends of which bars are freely connected to the bars 42 and 43 while their lower ends are freely mounted on a shaft 46 one end of which is secured to a crank arm 47 secured on the inner end of shaft 5, which shaft 46 extends transversely of the machine and has its opposite end secured to a crank arm 48 secured to a shaft 49 similar to shaft 5 rotatably mounted in a bearing 50 secured to the opposite side of the frame 1. The bars 44 and 45 are divided intermediate their length into lower and upper sections 51-52 and 53-54, the lower sections being provided with slots 55 towards their upper ends through which slots extend laterally pins 56 and 57 secured to the lower ends of the upper sections while the upper sections are provided with slots 58 through which extend laterally pins 59 and 60 secured to the lower sections adjacent their upper extremities, the pins being headed to hold the upper and lower sections together yet permitting the upper sections to be longitudinally movable on the lower ones so that by the insertion of springs 61 and 62 between the upper ends of the upper section slots and the upper ends of the lower sections, which springs are under compression when pressure is exerted on the inside of the front closure plate, the closure plate is yieldably supported on the bars 44 and 45 and thus undue pressure on the closure plate is relieved when in the act of compressing the sheaves in the basket.

The bottom of the basket, that is, the bottom when dumping, consists of a plate 63

formed substantially like a fork, although it may be made solid if desired, which plate is arranged to hang vertically in front of the open or wide end of the basket when the latter is horizontal, and it is attached freely at its opposite sides adjacent its upper edge to two normally horizontal side bars 64 and 65 fulcrumed intermediate their length and nearer to their rear ends on pins 66 and 67, which pins are rigidly secured to a suitable part of the basket supporting structure, such as the side extension plates, one of which is indicated by the numeral 68, there being one such bar secured to the respective plate bars 24 and 25. The rear, or free ends of the bars 64 and 65 are connected respectively by links 69 and 70 to pins 71 and 72 secured to the arms 73 and 74 of bell cranks 75 and 76 rockably mounted on the stud shafts 18 and 19, the links 69 and 70 being slotted, as at 77, to receive the pins 71 and 72, as will be more particularly referred to hereinafter, while to the opposite arms 78 and 79 of the bell cranks are connected the ends of levers 80 and 81 the opposite ends of which are freely mounted on shaft 46. Secured to the sides of the frame 1 forward of the basket and projecting inwardly are brackets 82 and 83 on which are pivotally mounted for upward tripping latches 84 and 85 arranged to be tripped by the fork-supporting bars 64 and 65 at a desired point in the operation of the basket and to resume their normal position to temporarily support the bars when the latter drop on the latches, as will be more fully described later. The latches are returned to their normal position after tripping by means of springs 86 and 87, as shown in Fig. 10.

The bell cranks 75 and 76 are each provided with an additional arm 88 and 89 respectively, which arms normally extend forwardly and are inclined downwardly, to which arms are freely connected levers 90 and 91 the opposite ends of which are freely connected to levers 92 and 93 intermediate the length of these levers, the shorter ends of levers 92 and 93 being pivoted to the lower side bars 27 and 29 while their opposite ends extend forwardly and are freely connected to the forward ends of bars 94 and 95 which are disposed longitudinally of the machine just below the lower edges of the side plates 30 and 31 and lie substantially at the same inclination as these lower edges, the rear ends of the bars 94 and 95 being freely connected to the lower ends of levers 96 and 97 the upper ends of which latter levers are freely connected, as at 98, to the rear ends of the upper side bars 26 and 28 respectively. Extending between the bars 94 and 95 and rigidly secured to them is a concavo-convex plate 99, which forms the bottom plate of the basket when horizontal and the back plate when dumping.

Secured to the side bars 26—27 and 28—29 between the rear end of the basket and the plate bars 24 and 25 are bars 100 and 101 each provided with an outwardly projecting pin 102 and 103 respectively freely connected to which are links 104 and 105 extending upwardly and forwardly the opposite ends of which links are freely connected to the ends of levers 106 and 107 fulcrumed on brackets 108 and 109 secured vertically to the frame 1 on opposite sides of it, these levers lying normally in a horizontal position and having their free ends engaging in the grooved peripheries of cams 110 and 111 secured eccentrically on shafts 5 and 49, the cams also being secured to the crank arms so that they move concurrently therewith. The cam grooves are indicated by the numerals 112 and 113 respectively.

Each cam is formed substantially heart-shaped, as shown more particularly in Fig. 11, to which reference should now be had, with the pointed end facing forwardly when the basket is in the horizontal or sheaf-receiving position, and the point of the cam lies normally on a horizontal axis *ab* taken through the centre *c* of its cam shaft 5, or 49 as the case may be, the rear length *ac* on the axis being shorter than the forward length *cb*. The centre *c* is eccentric with respect to the centre *d* which is the true cam centre and the rear end portion *ef* of each cam is formed, as to its periphery, as a true semi-circle the centre of which is the centre *d* so that this portion of the cam periphery is eccentric to the cam shaft, its ends terminating at *e* and *f* on a vertical axis taken through the cam centre *d*. The upper forward portion *eb* of the cam periphery is continued to the point *b* as a true curve the centre of which is the shaft centre *c* so that this portion is concentric with the shaft and travels through a true circle as the shaft is rotated. The remaining lower forward portion *fb* of the cam extends from the vertical axis *ef* to the point *b* in a curve eccentric to the shaft centre *c* and the cam centre *d*, the centre of which curve lies on a vertical axis taken through the cam centre *d* at a point near the upper end of the axis so that this curve is considerably flatter than that of the upper peripheral portion *eb*, all as shown in Fig. 11.

The lower ends of the bars 42 and 43 are provided with short extensions 114 and 115 spaced from the bars and forming with them jaws, indicated by the numeral 116 in Fig. 1, within which the upper edge of the fork plate 63 normally rests while to the lower side bars 27 and 29 are secured stop members 117 and 118 adapted to engage the lower members 119 and 120 of the frame 1 when the basket is in the horizontal position.

The stooker operates in the following manner: In Figs. 1, 2, and 3 the basket is shown in the open position ready to receive sheaves from the binder, the front closure plate 43^a being raised and the basket operating mechanism being out of operation. As the stooker is carried along by the binder the traction wheel 2 and sprocket 3 rotate continuously so that the sprocket 4 also rotates continuously, but freely, on the shaft 5. On a sufficient number of sheaves being deposited in the basket the operator actuates the rod 17 and crank 16 to withdraw the rod 15 clear of the lower end of the lever 13 whereupon the lower end of the lever swings downwardly, raising the upper end clear of the extension 12 of the pawl 10, so that the pawl drops into one of the teeth 9 of the clutch 7, being carried into engagement therewith by means of the spring with which it is provided, being spring-pressed, as hereinbefore stated. As the pawl is secured to shaft 5 this shaft is then set in motion, carrying round in a forward direction the cams 110 and 111, the crank arms 47 and 48, and the shaft 46, the basket at the same time swinging round on the stud shafts 18 and 19 until it reaches a substantially vertical position, being assisted in its swinging movement by the rearward movement or thrust of the levers 80 and 81 which swing the bell cranks 75 and 76 on the stud shafts, and while the swinging movement of the basket is taking place the front closure plate 43^a is being swung down to close the front of the basket by its bars 44 and 45 which are actuated by the moving shaft 46 as it is carried round by the crank arms, so that when the basket reaches the vertical, or dumping position, the front closure plate is disposed between the side plates 30 and 31 a sufficient distance to bear on and compress the sheaves against the back plate 99 to form a compact stook, undue strain on the plates being prevented, however, by the provision of the springs 61 and 62. In this position the remaining sides of the stook are slightly held under the compression of the plate springs 36 and 37 which are then bearing on the sheaves towards their upper ends so that the head of the stook is thus gathered up, as it were, all round and bunched into a neat form. During this movement of the basket from the horizontal position to the vertical the cams 110 and 111 are carried round with the crank arms through the curve distance *fb* and being eccentric as described they depress their respective levers 106 and 107 until these levers, with their links 104 and 105, are in position to hold or brace the sides of the basket temporarily against further swinging movement, when the points of the cam will be then bearing on the levers. This is shown in Fig. 4.

The basket, therefore, being in the vertical position, loaded, with the stook resting

vertically on the fork bottom plate and held meanwhile against further swinging movement by the cams, the links 104 and 105, and the levers 106 and 107, the crank arms 47 and 48 and the cams continue to rotate so that the bell cranks 75 and 76 are swung round on the stud shafts 18 and 19 by the continued backward thrust of the levers 80 and 81 to actuate the levers 90 and 91 which are connected to the bell crank arms 88 and 89, which levers 90 and 91 swing the levers 92 and 93 upwardly to raise the back plate 99 clear of the stook, while at the same time the slotted links 69 and 70 are drawn downwardly by the arms 73 and 74 of the bell cranks to swing the bars 64 and 65 upwardly to swing the fork or bottom plate 63 also upwardly clear of the basket and thus allow the stook to drop vertically to the ground, the bars 64 and 65 on their upward movement tripping and passing above the latches 84 and 85, and the front closure plate being meanwhile carried through between the sides of the basket to the full limit of the length of the bars 44 and 45, which are then practically horizontal, so that the front closure plate supports the stook against tilting over during its deposit on the ground when the bottom plate 63 is removed from underneath it. These positions of the back and bottom plates are shown by the full lines in Fig. 5 and that of the front closure plate by the dotted lines in the same figure.

During the movement just described the peripheral curved portions *eb* of the cams have been riding on the levers 106 and 107 but as these portions are concentric with the cam shaft no movement of the levers from the bracing position described has taken place so that the function of the cams during this period of the stooker operation is merely to maintain the levers in the bracing position.

Up to this point the crank arms have been travelling through substantially a half revolution and are now returning to their original position through the remaining half. Continuing to rotate, the operation of the levers 90-91 and 92-93 is reversed since the bell cranks 75 and 76 are now swung in the reverse direction by the forward pull of the levers 80 and 81 so that the back plate 99 is swung back again into its normal position. The action of the slotted links 69 and 70 is also reversed, thus swinging the side bars 64 and 65 and the fork 63 downwardly, the side bars, however, being intercepted on their downward movement by the latches 84 and 85 so that they rest on the latches 84 and 85 while the back plate is closing, being drawn forwardly by the return swinging movement of the basket from the vertical to the horizontal position caused by the forward pull of the levers 80 and 81 so that they, the side bars, drop off the latches, re-

turning the fork to the normal position. The object of thus temporarily supporting the side bars on the latches is to maintain the lower edge of the fork well clear of the ground while the basket is returning to its normal position to obviate possible damage to the fork through striking stones or other obstacles and it should be noted here that the fork plate, being freely connected to the bars 64 and 65, will swing and ride freely over any object in its path with which the lower edge may come in contact. While the bars 64 and 65 are being drawn rearwardly off the latches the pins 71 and 72 of the bell crank arms 73 and 74 travel freely in the slots 77 of the links 69 and 70 so that during that time the links do not actuate the bars 64 and 65.

As the crank arms continue to rotate the basket continues its return swing until when the crank arms have completed a full revolution, the basket is again in its normal horizontal sheaf-receiving position and simultaneously with its arrival in this position the top closure plate 43 is swung upward to its normal open position by the bars 44 and 45, while the eccentricity of the cams permits the levers 106 and 107 to resume their normal horizontal position. At the termination of the complete revolution the lower end of lever 13 strikes the rod 15, thus raising the lower end of the lever and swinging its upper end to depress the end 12 of the pawl 10 and disengage the pawl from the clutch 7 so that the sprocket 4 then continues to rotate while the operation of the basket and its mechanism is automatically stopped until it is again filled with sheaves and the rod 15 withdrawn to reengage the pawl in the clutch.

Attention should be drawn to the stop members 117 and 118, as these perform an important function in the operation of the machine, particularly in the opening of the basket, as, when the basket is tilted to the vertical position, the stops contact with the lower frame members 119 and 120, the position of the stops being shown by the full lines in Figs. 4 and 5 and by the dotted lines in Fig. 6, in which views stop 117 is shown, it being understood that stop 118 is in the same position on the other side of the machine. The two sides of the basket are thus held positively by the stop members against further tilting movement, the mechanism, however, continuing to operate, so that a quick-opening action of the basket is obtained in the manner already described.

It will be seen, therefore, that I have devised a stooker which is of great practical utility and in which the number of parts is reduced to a minimum so that its construction and operation is greatly simplified without detracting in the slightest degree from its efficiency and serviceability.

What I claim as my invention is:—

1. In a stooker, the combination with a main frame, of a fixed axis secured to said frame, a sheaf-receiving basket comprising a pair of normally horizontal side plates pivotally mounted on said axis and upper and lower plates forming the top and bottom closure plates of the basket when horizontal and the front and back plates when vertical, said top closure plate being normally in the open position, a suitably supported plate forming the front end closure plate of the horizontal basket and the bottom closure plate when vertical, said plate forming a platform on which the stook is supported, mechanism the operation of which tilts the basket about the said fixed axis to a substantially vertical position while closing the top closure plate, withdraws the said platform to deposit the stook and raises the back closure plate to clear the stook and then returns the back closure plate, the platform, the basket, and the top closure plate to their normal positions, means for operating the tilting mechanism, levers fulcrumed to the frame on opposite sides of the basket each connected at one end to it, and means whereby said levers are caused during the tilting movement of the basket to assume a position to maintain it tilted during the withdrawal of the platform and the back closure plate.

2. In a stooker, the combination with a main frame, of a fixed axis secured to said frame, a sheaf-receiving basket comprising a pair of normally horizontal side plates pivotally mounted on said axis and upper and lower plates forming the top and bottom closure plates of the basket when horizontal and the front and back plates when vertical, said top closure plate being normally in the open position, a suitably supported plate forming the front end closure plate of the horizontal basket and the bottom closure plate when vertical, said plate forming a platform on which the stook is supported, mechanism the operation of which tilts the basket about the said fixed axis to a substantially vertical position while closing the top closure plate, withdraws the said platform to deposit the stook and raises the back closure plate to clear the stook and then returns the back closure plate, the platform, the basket, and the top closure plate to their normal positions, means for operating the tilting mechanism, levers fulcrumed to the frame on opposite sides of the basket each connected at one end to it, and means whereby said levers are caused during the tilting movement of the basket to assume a position to maintain it tilted during the withdrawal of the platform and the back closure plate, said means being adapted without cessation of operation to maintain the levers in the assumed position during the operation of the said plate and to then permit return of the levers to their normal positions as the basket is returned to its horizontal position.

3. In a stooker, the combination with a main frame, of a fixed axis secured to said frame, a sheaf-receiving basket comprising a pair of normally horizontal side plates pivotally mounted on said axis and upper and lower plates forming the top and bottom closure plates of the basket when horizontal and the front and back plates when vertical, said top closure plate being normally in the open position, a suitably supported plate forming the front end closure plate of the horizontal basket and the bottom closure plate when vertical, said plate forming a platform on which the stook is supported, mechanism the operation of which tilts the basket about the said fixed axis to a substantially vertical position while closing the top closure plate, withdraws the said platform to deposit the stook and raises the back closure plate to clear the stook and then returns the back closure plate, the platform, the basket, and the top closure plate to their normal positions, means for operating the tilting mechanism, levers fulcrumed to the frame on opposite sides of the basket each connected at one end to it, and means whereby said levers are caused during the tilting movement of the basket to assume a position to maintain it tilted during the withdrawal of the platform and the back closure plate, said means being adapted without cessation of operation to maintain the levers in the assumed position during the operation of the said plate and to then permit return of the levers to their normal positions as the basket is returned to its horizontal position.

4. In a stooker, the combination with a main frame, of a fixed axis secured to said frame, a sheaf-receiving basket comprising a pair of normally horizontal side plates pivotally mounted on said axis and upper and lower plates forming the top and bottom closure plates of the basket when horizontal and the front and back plates when vertical, said top closure plate being normally in the open position, a suitably supported plate forming the front end closure plate of the horizontal basket and the bottom closure plate when vertical, said plate forming a platform on which the stook is supported, mechanism the operation of which tilts the basket to a substantially vertical position while closing the top closure plate, withdraws the said platform to deposit the stook and raises the back closure plate to clear the stook and then returns the back closure plate, the platform, the basket, and the top closure plate to their normal positions, means for operating the tilting mechanism, levers fulcrumed to the frame on opposite sides of the basket each connected at one end to it, and means whereby said levers are caused during the tilting movement of the basket to assume a position to maintain it tilted during the withdrawal of the platform and the back closure plate, said means being adapted to permit return of the levers to their normal position as the basket is returned to its horizontal position.

6
 centric cam for the opposite end of each lever operating concurrently with the mechanism aforesaid adapted to move the levers to assume a position to maintain the basket in the tilted position during the withdrawal of the platform and back closure plate and to permit return of the levers to normal position as the basket returns to its normal position, each said cam having a concentric portion designed to roll on its respective lever without moving it during the withdrawal of the platform and back closure plate.

5. In a stooker, the combination with a main frame, of a fixed axis secured to said frame, a sheaf-receiving basket comprising a pair of normally horizontal side plates pivotally mounted on said axis and upper and lower plates forming the top and bottom closure plates of the basket when horizontal and the front and back plates when vertical, said top closure plate being normally in the open position, a suitably supported plate forming the front end closure plate of the horizontal basket and the bottom closure plate when vertical, said plate providing a platform on which the stook is supported, mechanism the operation of which tilts the basket about the said fixed axis to a substantially vertical position while closing the top closure plate, withdraws the said platform to deposit the stook and the back closure plate to clear the stook and then returns the back closure plate, the platform, the basket, and the top closure plate to their normal positions, means for operating the tilting mechanism, and means whereby the return of said platform to its normal position is delayed for a predetermined interval during the return movement of the basket.

40. 6. In a stooker, the combination with a main frame, of a fixed axis secured to said frame, a sheaf-receiving basket comprising a pair of normally horizontal side plates pivotally mounted on said axis and upper and lower plates forming the top and bottom closure plates of the basket when horizontal and the front and back closure plates when vertical, said top plate being normally in the open position, a pair of normally horizontal platform bars fulcrumed on opposite sides of the basket, a plate extending between the forward ends of said bars forming the front end closure of the horizontal basket and the bottom closure plate when vertical providing a platform on which the stook is supported, mechanism the operation of which tilts the basket to a substantially vertical position while closing the top closure plate, operates said bars to withdraw the platform to deposit the stook and raises the back closure plate to clear the stook and returns the back closure plate, the platform, the basket, and the top closure plate to their normal positions, means for operating the

tilting mechanism, latches carried by the frame adapted to be tripped by the platform bars on the platform withdrawal movement and to intercept them on their return movement, and means included in said mechanism whereby the bars are carried through a predetermined distance to clear the latches.

7. In a stooker, the combination with a main frame, of a fixed axis secured to said frame, a normally horizontal sheaf-receiving basket pivotally mounted on said axis and normally open on one side to receive the sheaves and provided with a closure plate whereby the said open side may be closed, said plate being capable of passing between the basket side walls, means for tilting the basket about the said fixed axis to a substantially vertical position while moving said closure plate between the basket walls to compress the sheaves into a stook, said means being operative to tilt the basket back to its normal position after a predetermined interval and to move said plate to open it as the basket returns, means for supporting the stook in the vertical position in the closed basket, means for spreading the supporting means to deposit and clear the stook, and spring means carried by the basket walls between which the stook is sprung as the closure plate compresses it.

8. In a stooker, the combination with a main frame, of a fixed axis secured to said frame, a sheaf-receiving basket comprising a pair of normally horizontal side plates pivotally mounted on said axis and upper and lower plates forming the top and bottom closure plates of the basket when horizontal and the front and back closure plates when vertical, said top plate being normally in the open position, a pair of normally horizontal bars fulcrumed on opposite sides of the basket, a plate hung between the forward ends of said bars and swingable rearwardly as to its lower end forming the front end closure of the horizontal basket and the bottom closure plate when vertical providing a platform on which the stook is supported, mechanism the operation of which tilts the basket about the said fixed axis to a substantially vertical position while closing the top closure plate, raises said bars to withdraw the platform to deposit the stook and the back closure plate to clear the stook and returns the back closure plate, the platform, the basket, and the top closure plate to their normal positions, and means whereby said bars are intercepted and held in a raised position on their return movement to delay the return of the platform to its normal position.

9. In a stooker, the combination with a main frame, of a fixed axis secured to said frame, a sheaf-receiving basket comprising a pair of normally horizontal side plates

pivottally mounted on said axis and upper and lower plates forming the top and bottom closure plates of the basket when horizontal and the front and back closure plates 5 when vertical, said top closure plate being normally in the open position, a suitably supported plate forming the front end closure of the horizontal basket and the bottom

the basket, and the top closure plate to their normal positions, means for operating the tilting mechanism, and means for preventing tilting of the basket past the substantially vertical position, said means comprising stop members carried by the basket arranged to contact with the main frame coincident with the arrival of the basket in the
